UNITED STATES PATENT OFFICE.

DAVID GRANT PETRIE, OF BEXLEY HEATH, ENGLAND, ASSIGNOR TO YOUNG, OSMOND, & YOUNG, LIMITED, OF BEXLEY HEATH, ENGLAND, A BRITISH COMPANY.

ELECTRIC HEATING APPARATUS.

Application filed March 15, 1928, Serial No. 261,994, and in Great Britain March 21, 1927.

This invention relates to electric heating apparatus of the type wherein a frame, such as a tube, carries a resistance unit comprising a heat-resisting insulating base of strip form, 5 and an electrical conductor constituting a resistance element so mounted on said base as to be insulated from the frame. The invention has for its main object to provide a resistance unit of improved construction for apparatus of this type, in order to facilitate 10 the construction and erection of the apparatus, which may be used for heating rooms or as an immersion heater or otherwise.

According to an important feature of the 15 invention, there is provided in or for electric heating apparatus of the type described, a resistance unit having metallic edging that extends along one or both longitudinal edges of the base of the unit, for example of mica, 20 and is electrically connected to the resistance element, in order that the metallic edging may serve as a return wire for current passing through the resistance element, and thereby obviating the use of a separate return wire to 25 a terminal at one end of the heater.

According to another feature of the invention, a resistance unit as described in the preceding paragraph is combined with one or more insulators carried by it and arranged to 30 insulate the frame from the metallic edging that serves as a return conductor.

According to another important feature of the invention, there is provided in or for electric heating apparatus of the type described, a resistance unit comprising a base in the form of a plurality of pieces of insulation (e. g. mica) of strip form arranged end-to-end, and metallic edging extending along one or both of the longitudinal edges of the 40 pieces of insulation and serving to hold the same together, in combination with an insulator, or a plurality of insulators spaced apart, mounted on the resistance unit and arranged to insulate the metallic edging from the frame, for the purpose of supporting the resistance in the frame and improving the insulation of the resistance element.

Conveniently, each insulator aforesaid is in 50 the form of a plate, for example of mica, that lies transversely of the resistance unit and extends at one or both ends beyond, for example, through, the metallic edging of the base.

Other features of the invention relate to 55 the construction of the insulators mounted on the resistance unit.

The invention also provides electric heating apparatus of the type described above comprising a resistance unit in any of the forms set forth above.

The invention is illustrated diagrammatically and by way of example in the accompanying drawing, wherein:—

Figure 1 is a longitudinal section through part of an electric heater according to the invention comprising an improved construction of resistance unit, and

Figure 2 is a vertical cross-section taken on the line 2—2 in Figure 1;

Figure 3 is an elevation of a resistance unit according to the invention provided with various forms of insulators, and

Figures 4 and 5 are vertical cross-sections taken respectively on the lines 4—4 and 5—5 in Figure 3;

Figure 6 is a longitudinal section through part of an electric heater provided with another form of resistance unit and insulator according to the invention and

Figure 7 is a vertical cross-section taken on the line 7—7 in Figure 6.

Like reference characters designate like parts throughout the several views.

Referring first to Figures 1 and 2, an electric heater comprises a frame in the form of a single metal tube, or a number of such tubes connected end-to-end, which provide a continuous tubular passage 10 that is closed at one end by a cap 11. The other end of the passage, not shown, may carry an insulating block having two terminals, which block and terminals are preferably enclosed by a cap on the adjacent end of the tube or tubes.

A resistance unit in strip form comprises a base consisting of rectangular mica plates 12 arranged end-to-end, and metallic edging 13 of U-section connecting the plates together at their edges. This structure extends from end-to-end of the passage and carries a resistance element 14 in the form of a coiled resistance wire threaded through holes in the mica base constituted by said plates 12. As described so far this resistance unit is known in itself.

In a preferred form of construction of electric heater according to this invention, the resistance unit is insulated from the walls of the heater, and one terminal aforesaid has the adjacent end of the resistance wire 14 electrically connected to it and the other end of the wire is electrically connected to one or

both metallic strips 13 which are electrically connected to the other terminal aforesaid. This construction of heater is a very simple one as there is only a single length of resistance wire and only one row of perforations in the mica base, and no return wire is required although the two terminals are both at the same end of the heater.

Various forms of insulators for insulating the metallic edging from the outer tube or tubes will now be described, insulation 15, for example a mica disc or washer, being preferably interposed between the cap 11 and the adjacent ends of the metallic edging 13. As shown in Figures 1 and 2, an insulator in the form of a rectangular sheet 20 of mica or other convenient insulating material is arranged between the adjacent ends of two of the plates 12 and constitutes part of the base 20 of the resistance unit. This sheet 20 has at its ends semi-circular lugs 21 which extend through slots in the metallic edging 13 and constitute spacing pieces for spacing the latter away from the surrounding tube or tubes.

In a modified construction of insulator shown in Figure 1, two sheets 22 of mica or the like, one at each side of the plates 12, are riveted together by eyelets 23 and have their ends 24 extending beyond the edging 13. These extending ends 24 are preferably curved so as to present convex edges for bearing against the adjacent outer tube, whereby the insertion of the resistance unit in the outer tube is facilitated, as friction will be reduced, as is the case also with the lugs 21. In some cases only one sheet 22 may be used. The resistance wire may be threaded through the hollow rivets 23 and also through a perforation in the sheet 20, as illustrated.

In Figure 3 the insulator shown at the extreme left-hand of the figure differs from that just described in the preceding paragraph only in that additional rivets 34 which may be hollow are provided securing the sheets 22 to the metallic edging 13, a washer 25 being provided between the end of each rivet 34 and the adjacent sheet 22. These rivets lend rigidity to the insulator.

The construction of insulator shown in Figures 3 and 4 differs from that described in the preceding paragraph in that channel-shaped metal reinforcing elements 26 are used instead of the rivets 34 and serve to secure the ends of the sheets 22 to the metallic edging 13 and also to reinforce the sheets 22 against bending stresses acting transversely of the length of the sheets. These elements 26 are slotted each between their ends which are riveted to the metallic edging and serve also to reinforce the resistance unit against bending in the direction of its length.

The insulator shown in Figures 3 and 5 differs from those described above comprising sheets 22 in that it is reinforced against bending stresses acting in the direction of length

of the plates by a metal reinforcing element 27 of strip form threaded through two slots 28 in one of the plates 22 and having its ends bent on themselves and lying each in a recess 29 at the ends of the plates 22 which are thereby gripped and firmly held in position. This element 27 thus also serves to reinforce the resistance unit against bending stresses acting transversely of its length.

In each of the constructions of insulator described above the length of the insulator is preferably equal to the internal diameter of the containing tube so as to hold the resistance unit lying diametrically across the tube. If additional support is required, for example in a tube of larger diameter, say a three inch tube, as shown in Figures 6 and 7, the sheets 22 may have squared ends and carry on the same spring clips 30 of the form shown having laterally extending wings which will bear against the inner wall of the tubular passage 10 at both sides of the resistance unit. Such clips serve as locating means for positioning the resistance unit diametrically or substantially diametrically in the outer tube, and also serve as reinforcing means for the sheets 22 against bending stresses acting transversely on them. These clips 30 may be secured in position by rivets 31 which hold the adjacent ends of the sheets 22 firmly together. In some cases, particularly if the tubular passage 10 is short, only one such insulator need be provided.

The resistance element may be arranged in any convenient manner, for example rectilinearly, or zigzag, on the mica base. If desired, the resistance element may extend from end-to-end of the unit and be doubled on itself, the bend of the wire being connected electrically to the metallic edging. In this case three terminals will be provided, a separate control preferably being provided for each of the two connected to the element.

An important advantage of the invention is that it permits narrower strips of mica to be used than heretofore, whereby a considerable saving in cost of manufacture is effected. Even if the resistance element is not electrically connected to the metallic edging, which will then not serve as a return conductor, the improved construction of resistance unit provided with supporting insulators as described above has the advantage that the insulation of the resistance element is enhanced because even if for any cause, say owing to sagging, the element contacts with the metallic edging at one point, the circuit will not be put to earth.

Various modifications may be made in the details of construction described above without departing from the scope of the invention as defined in the claims. For example, other insulating materials besides mica, such as glass, earthenware and the like may be used for the base in certain cases. Also, a support-

ing insulator as described may be reinforced both longitudinally and transversely, for example by elements such as 26 and 27.

I claim:

5 1. For use with electric heating apparatus, a resistance unit comprising a heat-resisting insulating base of strip form, an electrical conductor constituting a resistance element mounted on said base, and metallic edging 10 that extends along at least one longitudinal edge of the base, is electrically connected to the resistance element, and serves as a return conductor.

15 2. For use with electric heating apparatus, a resistance unit comprising a heat-resisting insulating base of strip form, an electrical conductor constituting a resistance element mounted on said base, and metallic edging 20 that extends along at least one longitudinal edge of the base, is electrically connected to the resistance element, and serves as a return conductor, in combination with at least one 25 insulator carried by said resistance unit for insulating the latter from the frame of the apparatus.

30 3. For use with electric heating apparatus, a resistance unit comprising a base in the form of a plurality of pieces of insulation of strip form arranged end-to-end, an electrical conductor constituting a resistance element 35 mounted on said base, metallic edging extending along at least one of the longitudinal edges of the pieces of insulation and serving to hold the same together, and a plurality of 40 insulators spaced apart and mounted on the resistance unit for insulating the latter from the frame of the apparatus.

45 4. For use in electric heating apparatus, a resistance unit comprising a heat-resisting insulating base of strip form, an electrical conductor constituting a resistance element 50 mounted on said base, and metallic edging that extends along at least one longitudinal edge of the base, and is electrically connected to the resistance element, and serves as a return conductor; and an insulator of plate form that is mounted on said resistance unit, and lies transversely of the direction of length of the latter, and extends beyond each longitudinal edge thereof provided with metallic edging.

55 5. For use in electric heating apparatus, the combination of a resistance unit comprising a heat-resisting insulating base of strip form, an electrical conductor constituting a resistance element threaded through said base, and metallic edging that extends along at least one longitudinal edge of the base, and is electrically connected to the resistance 60 element, and serves as a return conductor; an insulator in the form of a thin plate that is mounted on said resistance unit, and lies transversely of the direction of length of the latter, and extends beyond each longi-

tudinal edge thereof provided with metallic 65 edging, and reinforcing means arranged to reinforce said insulator against bending stresses.

6. For use with electric heating apparatus, a resistance unit comprising a heat-resisting 70 insulating base of strip form, an electrical conductor constituting a resistance element mounted on said base, and metallic edging that extends along at least one longitudinal edge of the base, is electrically connected to 75 the resistance element, and serves as a return conductor; and an insulator comprising two sheets of thin insulating material placed one at each side of the base and riveted together through the latter and extending beyond each 80 longitudinal edge of the base provided with metallic edging.

7. For use with electric heating apparatus, the combination of a resistance unit comprising a heat-resisting insulating base of strip 85 form, an electrical conductor constituting a resistance element mounted on said base, and metallic edging that extends along at least one longitudinal edge of the base, is electrically connected to the resistance element, 90 and serves as a return conductor; an insulator comprising two sheets of thin insulating material placed one at each side of the base and riveted together through the latter and extending beyond both edges of the base, 95 and two spring clips mounted one on each end of the insulator.

8. An electric heater comprising in combination a metal frame in the form of a tube, and a resistance unit therein, which resistance 100 unit comprises a heat-resisting insulating base of strip form, an electrical conductor constituting a resistance element mounted on said base and metallic edging that extends along at least one longitudinal edge of the 105 base, is electrically connected to the resistance element, and serves as a return conductor.

9. An electric heater comprising in combination a metal frame in the form of a tube, and a resistance unit therein, which resistance 110 unit comprises an insulating base of thin material in strip form, an electrical conductor constituting a resistance element threaded through the said base and extending from end to end thereof, metallic edging that extends along both longitudinal edges of the base, is electrically connected to the resistance element, and serves as a return conductor, and a plurality of insulators mounted on said resistance unit in spaced relation along the 115 same, each of which insulators comprises two sheets of thin insulating material placed one on each side of the base and riveted together through the latter and extending beyond the metallic edging on both edges of the base. 120 125

In testimony whereof I affix my signature.

DAVID GRANT PETRIE.
